CLAIM

The ornamental design for an extended vehicle brushguard, as shown and described.

DESCRIPTION

FIG. 1 is a perspective view of the extended vehicle brushguard showing my new design;

FIG. 2 is a side elevational view thereof;

FIG. 3 is a top plan view thereof;

FIG. 4 is a front elevational view thereof;

FIG. 5 is a bottom plan view thereof; and,

FIG. 6 is a rear elevational view thereof.

The broken lines shown in FIGS. 1 and 2 are for illustrative purposes only and form no part of the claimed design.
